US0D1113545S

(12) **United States Design Patent** (10) Patent No.: **US D1,113,545 S**
(45) Date of Patent: ** Feb. 17, 2026

(54) **ARTICLE OF JEWELRY**

(71) Applicant: **LOUIS VUITTON MALLETIER**,
Paris (FR)

(72) Inventor: **Francesca Amfitheatrof**, Paris (FR)

(73) Assignee: **Louis Vuitton Malletier**, Paris (FR)

(**) Term: **15 Years**

(21) Appl. No.: **29/967,236**

(22) Filed: **Oct. 9, 2024**

(30) **Foreign Application Priority Data**

May 28, 2024 (FR) 20242396

(51) LOC (15) Cl. 11-01

(52) U.S. Cl.

USPC D11/11

(58) **Field of Classification Search**

USPC D11/3-8, 11-18
CPC A44C 25/001; A44C 25/002; A44C 15/00;
